(57) **CLAIM**

The ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof;

FIG. 9 is an enlarged view of the encircled portion in 9 FIG. 1;

FIG. 10 is an enlarged view of the encircled portion 10 in FIG. 4;

FIG. 11 is an enlarged view of the encircled portion 11 in FIG. 6;

FIG. 12 is an enlarged view of the encircled portion 12 in FIG. 8; and,

FIG. 13 is an enlarged view of the encircled portion 13 in FIG. 8.

The evenly-dashed broken lines in the figures depict portions of the electronic device that form no part of the claimed design.

The dot-dash broken lines encircling portions of the claimed design that are illustrated in enlargements form no part of the claimed design.

1 Claim, 13 Drawing Sheets
